UNITED STATES PATENT OFFICE.

CASSIUS D. THOMAS, OF MOBERLY, MISSOURI.

BRAKE MECHANISM.

No. 805,329.

Specification of Letters Patent.

Patented Nov. 21, 1905.

Application filed November 1, 1904. Serial No. 230,964.

To all whom it may concern:

Be it known that I, CASSIUS D. THOMAS, a citizen of the United States, residing at Moberly, in the county of Randolph and State 5 of Missouri, have invented new and useful Improvements in Brake Mechanism, of which the following is a specification.

My invention relates to certain new and useful improvements in brake mechanisms for 10 cars, the object in view being to provide a novel and improved construction of brake mechanism which insures economy of equipment and maintenance, efficiency in operation, and affords ready facility for repairs and 15 substitution of new for imperfect and worn-out parts.

With this and other objects in view the invention consists of the features of construction, combination, and arrangement of 20 parts hereinafter fully described and claimed, reference being had to the accompanying drawings, in which—

Figure 1 is a perspective view of a brake mechanism embodying my invention, one pair of brake-heads being detached from 25 their actuating-levers. Fig. 2 is a cross-section through the plank or beam and one of the supporting-brackets on which opposite levers of the sets of levers for actuating the 30 brake-heads are pivotally mounted, and Fig. 3 is a detail view of the operating or power-applying lever.

The numeral 1 in the drawings represents 35 a spring-plank or supporting-beam which, as shown, is formed of channel-iron, but may be of any improved form and construction and composed of metal, wood, or a composite structure, as desired. The brake-heads 2 are arranged in pairs upon opposite sides of this 40 beam, and the alining heads of the opposite pairs are movably mounted at the ends thereof upon pivoted hangers. In the present instance I have shown in the drawings one 45 brake-head of each set—namely, those arranged upon opposite sides of and at one end of the beam 1—this illustration being sufficient for a complete disclosure of the principles of the invention. The hangers 3 permit the heads 2 and their shoes to have 50 proper movement toward and from the car-wheels and adapt them to have sufficient independent play to conform thereto under varying resistance.

On opposite sides of the beam are two sets 55 of brake-levers A and B, the levers 9 and 10 of the set A being normally arranged at an

angle to the beam 1 with their inner ends projecting at a greater distance therefrom and pivotally connected to a fulcrum 12, provided at its forward end with spaced ears 13, 60 receiving an operating thrust-lever 14, having an opening 15 therein, through which passes a bolt 16 to pivotally connect it to said ears. As shown, the fulcrum 12 is provided with a central slot, opening through the sides 65 and rear end thereof to receive the inner and forward ends of the levers 9 and 10, which are pivoted therein upon the pivot-bolts 9' and 10', which project through said fulcrum. The levers 17 and 18 of the set B on the opposite or rear side of the beam 1 are arranged in a manner similar to the levers 9 and 10, except that the inner ends thereof project rearwardly at a corresponding angle and are pivotally mounted upon a fulcrum 12', formed 70 with a slot corresponding to that in the fulcrum 12 and provided with pivot-bolts 17' and 18', to which the said inner ends of the levers 17 and 18 are pivotally connected. From the rear end of the fulcrum 12' project ears 19, 75 forming a space to receive the rear end of a bottom rod or bar 20, which is pivotally mounted upon a bolt 21, extending through said ears, and is curved downwardly and forwardly to project beneath the beam 1 to a 80 point in advance thereof and has its forward end terminating in a bifurcated or forked extension 21, the arms of which are formed with openings 22 for the passage of a pivot-bolt 23, which bolt 23 extends through an 85 opening 24 in the lower end of the operating-lever 14 and pivotally secures the same between the arms. The lever 14 is in the form of a float-lever eccentrically mounted, the opening 15, through which its pivot 16 extends, being disposed below its center and closer to its inner and lower end, which is pivotally connected by the bolt 24 to the forked end 21 of the fulcrum-bar 20. The upper and forward end of the lever 14 is provided with an elongated slot 25, by which it 90 may be loosely and pivotally connected to an operating part.

The opposite levers of the two sets A and B are supported from the spring plank or beam 1 by carrier-brackets 26, each of which may comprise two plates or bars 27 and 28, arranged in parallel relation and fastened by the bolts 29 to the body portion of the beam 1. The ends of the bottom plate 28 are offset, as 95 shown at 30, to space the same from the ends of the plate 27, and thus provide the bracket 100 105 110

with forked terminals to receive the levers, which are pivotally mounted therein upon the bolts 31, passing through registering apertures 32 in the two plates. Instead of making the bracket 26 of two parts said bracket 5 may be of one single piece cast of malleable iron or steel. This construction of brackets permits the same to be readily and conveniently disconnected from the beam and as 10 readily connected thereto to permit of the removal of a worn or broken brake-lever and facilitate the application of a new brake-lever, the construction being such that this 15 operation, as well as all others in the way of repairing or substituting new parts for injured or worn-out ones, may be carried out by one man without assistance, thus enabling repair work to be accomplished at comparatively small expense.

20 The ends of the levers are pivotally connected by pins or bolts 33 and ears 34 on the brake-heads 2, so that when the upper and forward end of the float-operating lever 14 is forced rearwardly and the brake-levers swung 25 thereby the two sets of heads and shoes on opposite sides of the beam will be moved in opposite directions to engage opposite wheels upon the truck of a car. When the lever 14 is operated as above stated, it will thrust the 30 fulcrum 12 rearwardly, and thus swing the inner ends of levers 9 and 10 toward the beam 1 and project the outer end thereof and thrust the forward set of heads and shoes forward to engage the wheels against which 35 they are designed to act, and at the same time the bottom rod 20 will be drawn forward to swing the fulcrum 12' inward or toward the beam 1 to correspondingly swing the inner ends of the levers 17 and 18 and project 40 the outer ends to move the opposite or rear set of heads and shoes into engaging relation with another set of wheels. A reverse movement of the lever 14 swings the two sets of brake-levers in the opposite direction, as 45 will be readily understood, and releases or retracts the brake-heads 2.

It will be observed that the mode of arrangement of the opposite sets of brake-levers is such as to form toggles which enable high 50 brake-power to be applied to set the brake-heads 2, and that as the latter are hung from the pivoted hangers 3 they have ample freedom of movement to adapt themselves to variations of resistance upon coming in contact 55 with the wheels, so as to set up an effective brake-pressure. The adjustable connection of the lever 14 with the curved bottom rod or bar 20 permits the applied power to be varied at will to set the brakes with any degree 60 of force desired. Also it will be observed that the arrangement of the brake-levers effects the application of direct leverage to each separate brake-head, while the use of the fulcrum 12, which may be termed a 65 "twin" or "duplex" fulcrum, as it forms a

fulcrum member for the operating-lever and both brake-levers of the set A, enables one live lever to control two direct brake-levers. It will be further observed that each bracket 26 terminates in a fulcrum at each end, thus 70 adapting it to support two direct levers. This is an advantage, as well as the method employed of connecting each brake-head to a direct brake-lever by means of a loose pin or pivotal coupling 33. The brake mechanism 75 is especially advantageous in the fact that while it may be used in connection with dead levers the bottom rod or bar 20 obviates the necessity of employing said levers and their necessary supports, and said mechanism is further advantageous in the simplicity of its structure and the ease with 80 which a single workman without assistance may detach and apply any of the parts which require removal from age or injury or 85 have been accidentally broken and must be removed and new parts substituted therefor. As a result, economy of equipment and maintenance and safety and efficiency of operation are insured and the use of parts which 90 are liable to become detached and drop down upon the track-rails entirely avoided.

From the foregoing description, taken in connection with the accompanying drawings, the construction and mode of operation of 95 the invention will be understood without a further extended description.

Changes in the form, proportions, and minor details of construction may be made within the scope of the invention without departing from the spirit or sacrificing any of the advantages thereof.

Having thus fully described the invention, what is claimed as new is—

1. In a brake mechanism, the combination 105 of a support, opposite sets of divergently-arranged brake-levers fulcrumed to said support, brake-heads movably connected with the support and pivotally attached to the outer ends of the sets of divergent levers, twin 110 fulcrums attached to the inner ends of the said sets of divergent levers, an operating-lever pivoted to one of said fulcrums, and a bar or rod pivoted at one end to the other fulcrum and at the opposite end to the operating-lever.

2. In a brake mechanism, a supporting-beam, lever-carriers extending transversely of the beam and provided with terminal fulcrums at opposite sides thereof, opposite sets 120 of brake-levers mounted upon said terminal fulcrums, a fulcrum-piece pivotally connecting the levers of each set, a lever pivotally connected with one of the fulcrum-pieces, and a connecting member extending transversely 125 of the beam and pivotally connected with said lever and the other fulcrum-piece.

3. In a brake mechanism, two sets of divergent levers, a single operating-lever connected to one set, and a direct connection between 130

the operating-lever and the other set, whereby the movement of the single operating-lever will actuate both sets of brake-levers.

4. In a brake mechanism, a supporting-beam, sets of brake-levers disposed on opposite sides of said beam, means for directly operating one of said sets of brake-levers, and means extending transversely of said beam and forming a direct operating connection between said means and the other set of brake-levers.

5. Two sets of direct brake-levers, fulcrum devices connecting said levers, a bottom bar or rod directly pivoted to one of said fulcrum devices, and a lever directly pivoted to the other fulcrum device and to the said bottom bar or rod.

6. In a brake mechanism, a pair of direct brake-levers, an operating-lever, and a twin fulcrum-block operatively connecting said levers.

7. In a brake mechanism, two sets of divergent brake-levers, fulcrum-pieces connecting

the levers of each set, an operating-lever directly connected to one of said fulcrum-pieces, 25 and a rod or bar directly connecting said lever with the other fulcrum-piece.

8. In a brake mechanism, a fulcrum-block having opposite forked portions, direct brake-levers pivotally mounted in one of said forked portions, and an operating-lever pivotally mounted in the other forked portion.

9. In a brake mechanism, the combination of a support, opposite sets of divergent direct brake-levers, twin fulcrum-blocks operatively 35 connecting the levers of each set, an operating-lever pivoted to one of said blocks, and a direct connection between said lever and the other block.

In testimony whereof I affix my signature 40 in presence of two witnesses.

CASSIUS D. THOMAS.
